SPRING BAR

Jacob S. Feiner, New York, N. Y., and Lawrence L. Stone, Stamford, Conn., assignors, by direct and mesne assignments, to Charles B. Greenberg, New York, N. Y.

Application June 26, 1946, Serial No. 679,507

3 Claims. (Cl. 24—265)

1

This invention relates to spring bars for wrist watches, bracelets and other items of jewelry, and more particularly, spring bars of the type having a hollow tube, a trunnion slidably received at one or both ends of the tube and a compression spring within the tube forcing the trunnion or trunnions outwardly.

One object of the invention is to provide a spring bar of the type described having component parts, more particularly, trunnions, which are facilely and quickly assembled in position. In spring bars heretofore made the trunnions are not symmetrical so that each trunnion is required to be handled separately and examined carefully in order that its proper end be inserted in the tube. An allied object of the invention is to provide a spring bar construction in which the trunnions are symmetrical so that either end may be inserted in the tube indiscriminately without examination. This lends itself to simple, accurate and fast assembly, which may be automatic or semi-automatic, the improved trunnions being dumped into a hopper and individually fed from the mouth thereof.

A further object of the invention is to provide a spring bar of the type described having a structure, particularly, that of the trunnion, which will eliminate wobble and play of the parts and reduce stress repetition, fatigue and consequent failure. An allied object is to provide a trunnion having an increased bearing surface in the form of a "double bearing surface" comprising two widely spaced-apart bearing surfaces separated by a central recessed portion. A further object is to provide a trunnion having double bearing surfaces separated by a central annular recess adapted to cooperate with one or more indentations on the tube inwardly projected into the annular recess to retain the trunnion within the tube.

For the attainment of the foregoing and such other objects of invention as may appear or be pointed out herein we have shown several embodiments of our invention in the accompanying drawing, wherein:

Figure 1 is a top view of one form of improved spring bar, showing a fragmentary portion of the jewelry item to which it is applied;

Figure 2 is a top view of the improved trunnion used in the spring bar of Figure 1;

Figure 3 is a top view, partially sectionalized, of a portion of a second form of spring bar, employing the improved trunnion of Figure 2;

Figure 4 is a top view, partially sectionalized,

2

of a portion of a third form of improved spring bar;

Figure 5 is a top view of the improved trunnion used in the spring bar of Figure 4;

5 Figure 6 is a top view, partially sectionalized, showing a fourth form of improved spring bar, showing a portion of the jewelry item to which it is applied; and

10 Figure 7 is a top view of the improved trunnion used in the spring bar of Figure 6.

The type of spring bar to which this invention relates includes a tube, such as 1, Figure 1, which is to be removably secured between a pair of spaced supporting elements, such as the spaced 15 lugs 9, projecting from the wrist watch 8 or other item of jewelry. Spaced lugs 9 are provided with aligned openings 7 on their inner, opposing faces. As shown in Figure 1, openings 7 do not extend through to the outer faces of the lugs; this 20 form of spring bar connection, referred to as "blind," is preferred because an opening on the outer faces of the lugs would mar their appearance and interfere with any design engraved thereon. In some cases, known as "through" 25 connections, apertures, such as 6, Figure 6, extend through the lugs.

The spring bar is further provided with a reduced stem projecting outwardly at each end of its tube and adapted to be received within the 30 openings (7, Figure 1, 6, Figure 6) of the lugs. At least one of the stems is an integral part of an element known as a "trunnion" which is slidably retained within the tube and spring pressed to project its stem outwardly of the encasing 35 tube. The trunnion permits the spring bar to be inserted in, and removed from, its secured position between the lugs, by forcing the trunnion inwardly against the spring to engage its stem, or to free its stem from engagement, in the lug 40 opening. In some cases one of the stems is formed out of the tube material or may be fixedly secured at one end of the tube. In other cases, a trunnion is provided at each end of the tube. This is the form illustrated in the drawing. Also, 45 the invention applies equally to blind connections, Figure 1, or through connections, Figure 6.

In Figure 1, trunnion 10, one at each end of tube 1, shown in Figure 2, has a central portion comprising a pair of intermediate cylindrical 50 portions 11, 12, separated by a central annular recess 13, presenting bearing surfaces slidably engaged with the interior surface of tube 1. The trunnions 10, 10 are urged outwardly by a helical compression spring 5 within the tube but are retained within the tube against the force of the

spring by one or more projections 4 formed by indenting the tube material inwardly. Indentations 4 project into the annular recess 13 of the trunnions and are abutted by the spring-pressed trunnions at the annular shoulder defining the inner wall of cylindrical portions 11, 12 and one wall of annular recess 13. Projecting outwardly of cylindrical portions 11, 12 and centrally located on the longitudinal axis L—L, Figure 2, of the spring bar are reduced stems 15, 14, respectively. One of the stems, such as the stem 14 of the trunnion at the right end of the tube, Figure 1, is received in the opening 7 of the supporting lug 9. The indentations 4 are positioned at a predetermined distance from the ends of the tube so that a stem, such as the stem 14 of the right trunnion, will project outwardly beyond the tube a predetermined extent so that it may be readily fitted into the opening 7, the spring bar being then held securely between the spaced lugs 9, 9 by the compressive force of spring 5, and so that the spring bar may be removed from the lugs by forcing the trunnion into the tube, against the outward urgency of the compression spring, to clear the stem from engagement with opening 7.

The dimension of the cylindrical portion, such as the cylindrical portion 12 of the trunnion at the right end of the tube, Figure 1, and the said predetermined position of indentations 4 are such that a predetermined part of the cylindrical portion, designated 12^X in Figure 1, extends beyond the end of the tube. It is required that the cylindrical portion extend beyond the end of the tube so that the outer wall of the cylindrical portion may abut the inner wall of supporting lug 9 at a point beyond the end of the tube, to enable a blade or other instrument to be forced between the abutting walls. The distance of outward extension 12^X of the cylindrical portion is such that the trunnion may be forced into the tube a sufficient distance—limited by the abutment of the blade or instrument with the end of the tube—to enable the stem to be cleared from the opening 7.

The trunnion of the improved spring bar, such as the trunnion 10, Figure 2, is made symmetrical about a plane S—S transversely disposed, i. e., normally to the longitudinal axis L—L of the trunnion, at a central point thereof. By reason of the symmetrical formation of trunnion 10, its stems 14, 15 are identically dimensioned and equidistanted from the plane of symmetry S—S, and its cylindrical portions 11, 12 are likewise identically dimensioned and equi-distanced from S—S; finally, annular recess 13 is centrally divided by the plane of symmetry S—S. As a result of the said symmetrical formation of trunnion 10, either end may be indiscriminately inserted in the tube of the spring bar. For example, one trunnion 10 is inserted into the tube, Figure 1, at the right thereof with stem 15 and cylindrical portion 11 foremost so stem 14 and an extent 12^X of cylindrical portion 12 project beyond the tube. It is immaterial which end of the trunnion is inserted in the tube; the trunnion could as well have been inserted with stem 14 and cylindrical portion 12 foremost, as is shown in connection with the trunnion at the left of the tube, in which case stem 15 and extent 11^X of cylindrical portion 11 project beyond the tube. Irrespective of which end of the trunnion is inserted in the tube, the stem (whether stem 14 at the right, Figure 1, or stem 15 at the left) projecting from the tube will be identically dimensioned and will project the same distance beyond the tube; like-

wise, the extent of cylindrical portion (whether 12^X at the right, Figure 1, or 11^X at the left) projecting from the tube will be the same.

The helical spring 5 of the improved spring bar is such that the diameter of its central, inner space is sufficiently large to enable the stem 14, 15 of the trunnion to be received therein, as shown in Figure 1, so that either end of the trunnion may be inserted in the tube and the 10 inserted stem will be received in the inner space of the spring. The retaining projections 4 may be indented in the tube wall after the trunnion or trunnions have been inserted in the tube, or the tube may be first indented and the trunnion or trunnions subsequently inserted, the tube material having sufficient yieldability or resilience to permit the leading cylindrical portion 11, 12 to be forced inwardly beyond the projections 4.

The improved symmetrical trunnion 10 of Figure 2 may be used in a second type of spring bar shown in Figure 3 wherein the end of the tube 16 is crimped or spun over at 17 to be received within the annular recess 13 of the trunnion to retain it within the tube against the urgency 20 of compression spring 5 and with stem 15 as well as one cylindrical portion 11 entirely beyond the end of the tube. The parts are designed so that the stem and the cylindrical portion will be disposed at predetermined positions from 25 the end of the tube. By reason of the symmetrical formation of the trunnion either end may be inserted in the tube so that at all times a stem (whether stem 14 or 15) and a cylindrical portion (whether 12 or 11) will be disposed at the said 30 predetermined positions.

A third type of spring bar is shown in Figure 4 wherein the trunnion 20 has a central cylindrical portion 23 on both sides of which are annularly recessed or reduced portions 21, 22, and reduced 40 stems 24, 25 extending from annularly reduced portions 21, 22. Central cylindrical portion 23 is in slidable engagement with the inner surface of tube 16, and the trunnion retained within the tube by crimping or spinning the end 17 of the tube over the central cylindrical portion 23 of the trunnion, the inwardly turned end 17 being received in the annular space provided by annularly reducing portions 21, 22. The reduced portions 21, 22 thus enables the end of the tube 50 to be crimped over, and also provides a part projecting beyond the end of the tube, which projecting part functions in inserting and removing the spring bar as more fully explained with reference to projecting part 12^X, Figure 1.

Trunnion 20, Figures 4 and 5, is symmetrical about central transverse plane S—S, Figure 5, so that either end of the trunnion may be indiscriminately inserted in the tube and there will, at all times, project from the end of the tube a 60 stem (whether 24 or 25) of identical dimension and disposed at the same predetermined distance from the end of the tube, and a predetermined extent of a reduced portion (whether 21 or 22).

The type of spring bar illustrated in Figure 1, 65 Figure 3, and Figure 4 may be used in either the blind connection (described above with reference to Figure 1)—by reason of the projected portion of the trunnion (such as portion 12^X, Figure 1, the cylindrical portion 11, Figure 3, or the extended portion of 21, Figure 4)—or in the through connection (described below with reference to Figure 6). The fourth type of spring bar shown in Figure 6 employing the improved trunnion 30 shown in Figure 7 can be used only with 70 75 the through connection (as shown in Figure 6)

as it can be removed only by forcing the trunnion into the tube by applying a force at the end of the stem, such as 34, exposed at the outer face of supporting lug 9. Trunnion 30 has a central cylindrical portion 33 and reduced stems 34, 35 on each side thereof and is retained within the tube 16 by crimped end 17 thereof. Trunnion 30 is symmetrical about central transverse plane S—S so that either end of the trunnion may be indiscriminately inserted in the tube to project a 10 stem (whether 34 or 35) of identical dimensions beyond the end of the tube.

A troublesome objection to spring bars as heretofore made is the wobble and play of the parts, particularly at the trunnion, which causes stress repetition, fatigue and consequent wear and failure and loosening of the spring bar. We have overcome this objection by providing a spring bar, see Figure 1, in which trunnion 10 has increased bearing surface at the spaced cylindrical portions 11, 12; the provision of spaced bearing surfaces, one at cylindrical portion 11 and the other at cylindrical portion 12, reduces wobble and play and at the same time utilizes the central recess 13 for retaining the trunnion within the tube, by 25 the indented projections 4, as already described.

We claim:

1. An improved trunnion for use in a spring bar of the type having a tube, an inwardly extending stop on the tube and a trunnion at at least one end of said tube, said improved trunnion comprising a central portion annularly recessed to present a pair of spaced intermediate cylindrical portions, at least one of the said cylindrical portions being adapted for slidable engagement with the interior surface of the tube and adapted to engage said stop, said central recessed portion being proportioned for receiving therein said stop, and a reduced stem extending outwardly from each of said cylindrical portions, said stems, cylindrical portions and annular recess being symmetrical about a central transverse plane through the improved trunnion, whereby either end of the improved trunnion may be inserted in the said tube to present a stem of predetermined dimensions projecting a predetermined extent outwardly of the tube.

2. A spring bar of the class described comprising a tube, a trunnion at at least one end thereof, and a compression spring within the tube bearing against the trunnion and urging it outwardly, said trunnion having a central portion annularly recessed to present a pair of spaced intermediate cylindrical portions and a 50 reduced stem extending outwardly from each of said cylindrical portions, projections indented

inwardly of the tube material and received within the said annular recess of the trunnion to retain the same within the tube against the urgency of said compression spring, said projections being disposed relative to the end of the tube such that the said stem will project a predetermined distance beyond the tube and a predetermined extent of the cylindrical portion will project beyond the tube, said trunnion being symmetrical about a central transverse plane whereby either end of the trunnion may be inserted in the tube to project a stem at the said predetermined distance, and to project the said predetermined extent of a cylindrical portion, beyond the end of the tube.

3. A spring bar of the class described comprising a tube, a trunnion at at least one end thereof, and a compression spring within the tube bearing against the trunnion and urging it outwardly, said trunnion having a central portion annularly recessed to present a pair of spaced cylindrical portions and a reduced stem extending outwardly from each of said cylindrical portions, projections indented inwardly of the tube material and received within the said annular recess of the trunnion to retain the same within the tube against the urgency of said compression spring, said projections being disposed relative to the end of the tube such that the said stem will project a predetermined distance beyond the tube, the said cylindrical portions presenting double bearing surfaces slidably engaged with the interior surface of the tube, and spaced apart to increase the effective bearing 35 surface of the trunnion, said trunnion being symmetrical about a central transverse plane.
